CLAIM

The ornamental design for a backpack decoration, as shown and described.

DESCRIPTION

The patent or application file contains at least one drawing executed in color. Copies of this patent or patent application publication with color drawing(s) will be provided by the Office upon request and payment of the necessary fee.

1. Backpack decoration

FIG. 1.1 is a perspective view of a backpack decoration showing the new design;

FIG. 1.2 is a front perspective view thereof;

FIG. 1.3 is a right side perspective view thereof;

FIG. 1.4 is a left side perspective view thereof;

FIG. 1.5 is a top perspective view thereof;

FIG. 1.6 is a bottom perspective view thereof; and

FIG. 1.7 is a back perspective view thereof.

The portions of the backpack decoration that are colored in blue form no part of the claimed design.

1 Claim, 7 Drawing Sheets
